J. E. Maynard,
ATTORNEY.

UNITED STATES PATENT OFFICE

HENRY M. HALLS, OF LOS ANGELES, CALIFORNIA

MOISTURE STRAINING PRESS MAT

Original application filed October 1, 1928, Serial No. 309,621. Divided and this application filed August 23, 1930. Serial No. 477,437.

This invention relates to dehydrating presses and more especially to press mats for use in machines of the class shown in my application Ser. No. 309,621, filed Oct. 1, 1928, and of which this application is a division.

A purpose is to provide a simple, practical, substantial and very durable and highly effective strainer mat for such presses.

A further object is to provide a mat of such structural embodiment that it will readily flex over driving drums and rollers and yet will have a great degree of rigidity on transverse lines so that it will not sag or trough when under pressure in the machine.

The invention consists of certain advancements in the art as will be set forth in the ensuing disclosure and having, with the above, additional objects and advantages, and whose construction, combination and details of means, and the manner of operation will be made manifest in the description of the herewith illustrative embodiment; it being understood that modifications, variations and adaptations may be resorted to within the scope, principle and spirit of the invention as it is more directly claimed herein-after.

Figure 1 is a plan of the improved strainer mat.

Figure 2 is a cross-section of the mat.

Figure 3 is a longitudinal section of a fragment of the mat.

A preferred form of the mat consists of strong, fiber selvage ropes 75 and intermediate warp cords 76 laid in pairs one over and one under cross-cords or weft 77 over-bound on the selvage ropes.

Means are incorporated in the mat weave to transversely stiffen the body and consists of small wire rods 78 lying beside the cords 77 and having their ends wrapped on the ropes 75. Thus if a wire breaks it is still tied to the selvage ropes.

The selvage of the mat is bound with a rubber impregnation 75a.

This structure affords great flexibility along the mat and also provides a desired stiffness against any sagging of the mat transversely; the transverse rods allowing the selvage and mat to bend over rollers and

yet providing a bed which is reinforced from side to side.

This strainer is especially useful in apparatus for expressing moisture from peat or other fibrous vegetable matter which cannot be successfully accomplished by ordinary strainer cloth or by wire screen for the reason that the fine loose fibre will pack in the cloth interstices and will prevent the liquid from passing through the screen. Preferably, the warp cord is a rather heavy loose cord twine, which is particularly effective for straining quality of mat because the heavy loose cord, when pressed down, forms a strainer permitting a ready flow of the moisture through it and preventing the particles of the pressed fibrous material from passing through the mat. The compressed fibrous material peals freely from the mat surface and the soft cord expands to its ordinary size while the belt is traveling its orbit and back to the pressing position; the ready pealing of the matter preventing the clogging of the mat mass and thus permitting this to retain its high straining efficiency. The transverse rigidity of the mat is preserved by the transverse reinforcement wires which sustain the woven mat body while traversing press bed crevices and also operating to prevent shrinkage and expansion as well as preventing sagging.

The woof cord is preferably hard spun hemp or other fiber cord of desired strength and is, as before stated, much larger in diameter than the transverse metal bars so as to prevent the wire from cutting the warp cords while under pressure.

As shown, the wires 78 are straight and thus inextensible so that the mat will not expand laterally under pressure, and additional, the wires materially truss or reinforce the mat against sagging transversely. The wire cross parts connect to the selvage ropes by means of helical loops which provide a desired flexibility of the attachment as the mat bends around the usual tumblers in belt press apparatus.

What is claimed is:

A cloth press mat for dehydration which comprises heavy selvage cords and a warp system of cords, a system of straight-wire,

transverse reinforcing connecting and twisted along the selvage cords to prevent lateral spread thereof under pressure, and a weft system of cords each of which is of materially greater size than the selvage tie wires, said wires lying close to adjacent weft cords and free thereof the selvage twists of the wire being embedded in a heavy rubber selvage strip.
